ELECTROLYTIC CONDENSER

Paul McKnight Deeley, New York, N. Y., assignor
to Cornell-Dubilier Corporation, New York,
N. Y., a corporation of New York

Application December 7, 1935, Serial No. 53,367

5 Claims. (CL 220—44)

My invention relates to condensers in general and has particular reference to electrolytic condensers, preferably wet electrolytic condensers, although not limited to condensers of this type.

5 The general type of wet electrolytic condenser to which the present invention appertains consists briefly of a container adapted to accommodate an electrolyte solution and an electrode immersed in the electrolyte and constructed in 10 a convenient manner, such as in the form of a strip or sheet of metal, preferably aluminum, wound into a spiral, or folded back and forth upon itself in the manner of accordion pleating, or formed into a helicoidal surface as described 15 in detail in my copending application Serial No. 28,033 filed June 24, 1935; such electrode having a very thin coating of a dielectric film electrolytically formed thereon in a manner well known in the art.

20 In condensers of the foregoing general character, it is customary if not essential to provide venting means for the interior of the electrolyte container for the purpose of enabling the gas which is formed above the electrolyte during 25 operation of the condenser due to heating or other chemical or physical causes to escape from the container.

It has already been proposed to provide a vent in the form of a thin perforated rubber sheet, the 30 perforation having the size of a small pin hole in such a manner that under normal conditions; that is, when the condenser is not in operation, the pin hole is fully closed and exposure of the electrolyte to the outside atmosphere and seep- 35 ing or leaking through the pin hole is substantially prevented. When the condenser is in operation and heated, due to the electric current passed therethrough, the gas developed in the container causes the pressure therein to in- 40 crease whereby the rubber diaphragm is caused to distend or blow up. As a result the pin hole perforation is momentarily enlarged, permitting the excess gas to escape thereby relieving the 45 excess pressure within the container. After the gas has escaped, the rubber sheet or other flexible member assumes its normal position in which the pin hole is closed and the interior of the container sealed from the outside atmosphere.

When using a vent of the above described 50 general characteristic, consisting of a thin dia- phragm of rubber or other flexible material con- 55 veniently mounted in a wall of the container, preferably the bottom or top end wall, disadvan- tages are experienced by reason of the fact that 55 the vent is subject to damage during shipment

and handling and due to the likelihood of its becoming clogged or obstructed by foreign matter, such as dust and dirt and other obvious defects.

The object of the present invention is to provide a vent construction of improved character for electrolytic condensers which is substantially free from the disadvantages heretofore experienced in similar constructions in the art and which is simple in construction and design and 10 efficient and reliable in operation.

Further objects and novel aspects of the invention will appear hereinafter from the detailed description taken with reference to the accom- 15 panying drawing wherein:

Fig. 1 is an elevational cross-sectional view through an electrolytic condenser mounted upon a support or chassis and embodying the features 15 of the present invention.

Fig. 2 is a top view of a condenser according 20 to Fig. 1.

Fig. 3 is a cross-section of the condenser shown in Fig. 1 taken on line 3—3 of Fig. 1.

Fig. 4 is an enlarged cross-section of the de- 25 pending neck portion of the condenser accord- ing to Fig. 1 taken on line 4—4.

Fig. 5 is an enlarged perspective cross-section- 30 al view of a combined sealing gasket and breather diaphragm associated with the top and cap of the condenser shown in Fig. 1.

Similar reference characters identify similar 35 parts in the different views of the drawing.

Referring to the drawing, the condenser shown 40 therein comprises a metallic container 1 prefer- ably of cylindrical shape and consisting of a suitable metal such as aluminum or the like well known in the art. The container has a bottom wall 11 and a top wall 13, the latter hav- 45 ing a combined sealing gasket and vent or breather diaphragm associated therewith as will be described hereinafter. The bottom end wall 11 has an enlarged, preferably screw-threaded hollow attachment neck portion as shown at 2 serving for mounting the condenser on a support or chassis 3 in an upright position in accordance 45 with the usual practice in the art as shown in the drawing.

The anodic member or filmed electrode shown 50 at 4 which is supported by the riser rod 5 in the example illustrated, consists of a sheet or strip of suitable film forming material, preferably high purity aluminum of relatively small thickness which is folded back and forth upon itself in the manner of accordion pleating and riveted or otherwise secured to the riser rod 5. For this 55

purpose the rod 5 is preferably swaged or flattened throughout its entire upper part being in contact with the electrode 4, and provided with dish-shaped depressions enabling an easy and efficient connection of the central pleat of the anode by means of rivets or any other connection as shown at 6 in the drawing. The pleats of the anode in the example shown are of different widths, being largest in the middle and decreasing towards both ends as seen more clearly from Fig. 3 and should have sufficient rigidity to provide a self-supporting anode structure. By this method of folding a considerable length of foil may be placed in a small circular space, thus providing an anode of large capacity for a minimum of size and bulk of the condenser unit. An additional feature of this construction is that the over-all electrically resistive paths from the anode member to the wall of the circular container is reduced to a minimum thus effecting an improvement in electrolytic condenser structures in the form of reduced power factor or equivalent resistance. The rivets 6 should be of the same material as the rod 5; that is, high purity aluminum according to the above example. The rod 5 should also be of film forming metal such as aluminum as it is a part of the anode member. In this manner corrosion effects at the joints between the rod 5 and the anode 4 are prevented.

The carrier or riser rod 5 is forced through a resilient plug 7 of relatively flexible insulating material, such as rubber, said rubber plug being in turn forced into the container neck 2. The lower unthreaded part of the neck 2 is deformed or crimped to form axial depressions 2' uniformly spaced around the neck 2, to secure a liquid tight seal between the neck 2, the rubber plug 7 and riser rod 5, as seen more clearly from Fig. 4. The crimping of the neck can also be done by one or more circular grooves in place of axial grooves shown in the drawing as will be understood. The lower end of the riser rod projecting through the plug 7 constitutes the terminal of the anode and may be provided with suitable electrical connecting means, such as a clamping screw or soldering lug shown at 8, which may be either riveted on to the rod 5 or forced on or otherwise suitably connected therewith to secure efficient electrical contact.

In order to prevent the anode 4 from coming in accidental contact with the wall of the container, a spacing element of suitable insulating material which is not attacked or affected in any way by the electrolyte, such as a cylindrical spacer 9 of hard rubber, Celluloid or the like, is arranged between the anode and the inner wall of the container. In order to insure free access of the electrolyte to both the container and the anode surface, the spacer 9 is provided with a plurality of perforations 10 of suitable size and spacing as shown in the drawing.

The top end of the container is shown to be closed by a pair of disc-shaped cover members 13 and 14, the latter consisting of flexible material such as rubber and serving as a combined sealing gasket and vent or breather diaphragm while the former may consist of metal and serves to protect the vent or breather diaphragm against outside interference. The upper edge of the container is shown to be bent at first inwardly and then in an outward direction perpendicularly to the axis of the container in such a manner as to provide a rim or flange shown at 15. Both the cover 13 and the combined rub-

ber gasket and vent diaphragm 14 are provided with mid portions forming cup-shaped depressions as shown at 16 and 17 which fit inside of the container 1 at 18.

The gasket and vent 14 fits directly inside of the container while the cover proper 13, fits in turn inside the rubber gasket 14 as shown in the drawing. The outer edges or rims of the gasket 14 and the cover 13 are then spun over the rim or flange 15 of the container 1 and into liquid tight engagement therewith, whereby the rim or outer portion of the gasket 14 acts as a sealing washer in securing a liquid tight joint and preventing the electrolyte solution from leaking out during the shipment or handling of the condenser. The center portion or cup-shaped depression 17 is formed as a vent or breather diaphragm and provided for this purpose with a thin center section as seen more clearly at 19 in Fig. 5. The center section 19 has a perforation or aperture of pinhole size closed under normal conditions and preventing exposure of the electrolyte in the container to the outside atmosphere. In order to enable the mid portion 17 to expand or distend readily under the influence of excess pressure developed in the container, I have shown the mid portion 18 of the cap 13 of convex or outwardly arched or vaulted construction so as to allow the rubber diaphragm under internal pressure to distend and curve up like a balloon and open the perforation in the thin center section 19. In order to enable the gases passing through the perforation or pin hole in the section 19 to escape to the outside, I have furthermore shown the outer cover 18 provided with apertures or escape holes 20 of suitable size and spacing, as seen from Fig. 2.

In this manner the container is under normal conditions sealed from the outside atmosphere and may be handled and shipped with great facility without any likelihood of damage to the interior of the container or likelihood of loss or leakage of the electrolyte from within the container as well as damage due to the clogging or obstruction of the vent opening. As will be understood, the cover 13 does not have to be of aluminum or other film forming metal as it does not come in contact with the electrolyte in the container.

In order to prevent the mid portion of 17 of the rubber gasket from obstructing the escape holes 20 in the outer cover 18 under great excess pressure in the container, I have shown the gasket portion 17 to be provided with integral protuberances or elevations 21 suitably arranged around the thin center portion 19 and acting as spacing elements in preventing the diaphragm 17 from completely closing and obstructing the escape holes 20.

As will be understood, the anode may be formed with a dielectric film by any one of the known methods in the art and the forming may be carried out either before or after mounting in the condenser structure. When using aluminum as electrode metal, an electrolyte consisting of a mixture of borax, boric acid and water has been found to give satisfactory results. Furthermore the anode may have its surface increased by a roughening or chemical etching process to secure an unsmooth surface with minute depressions and elevations followed by the overlying dielectric film with the result of a substantial increase of the capacity of the condenser as is well understood.

As will be evident from the above, the inven-

tion is not limited to the specific construction shown in the drawing for illustration but is susceptible of modifications and variations coming under its broadest scope as defined in the appended claims.

I claim:

1. A vent structure for an electrolytic condenser or the like having a cylindrical container subject to internal excess gas pressure, comprising a cap having an outer flange and an inner outwardly arched apertured portion, said cap being secured to an open end of said container with its flange forming a narrow gap with the container, a diaphragm having an outer rim and a punctured central portion, the outer rim of said diaphragm being disposed within said gap to effect a liquid and gas tight seal between said container and said cap, the inner portion of said diaphragm underlying said cap, and spacing means intervening between said diaphragm and said cap and surrounding the punctured section of said diaphragm, whereby said diaphragm is adapted to distend underneath said cap at first in its entirety until prevented by said spacing means, whereupon only the punctured section will distend further under the action of excess gas pressure developed within said container.

2. A vent structure for an electrolytic condenser or the like having a cylindrical container subject to internal excess gas pressure, comprising a cap having an outer flange and an inner outwardly arched apertured portion, said cap being secured to an open end of said container with its flange forming a gap with the container, a diaphragm having an outer rim and a punctured inner portion, the outer rim of said diaphragm being disposed within said gap to effect a liquid tight and gas tight seal between said container and cap, and integral spacing elements of said diaphragm surrounding its punctured section and intervening between the diaphragm and said cap.

3. A vent structure for an electrolytic condenser or the like having a container subject to internal excess gas pressure, comprising an outwardly arched apertured cap having its edge secured to an opening of said container, a normally flat rubber diaphragm having a punctured center section of lesser thickness than its outer

portion, the edge of said diaphragm being disposed within the gap formed by said cap and said container to effect a liquid tight and gas tight seal between said cap and said container, said diaphragm spanning said opening underneath said cap, and spacing means surrounding said center section intermediate said diaphragm and said cap, whereby said diaphragm is adapted to distend underneath said cap at first in its entirety until prevented by said spacing means whereupon only said center section will distend further by the action of gas pressure developed in said container.

4. A vent structure for an electrolytic condenser or the like having a cylindrical container subject to internal excess gas pressure, comprising an outwardly arched apertured cap having its edge secured to an open end of said container, a normally flat rubber diaphragm having a punctured center section of lesser thickness than its outer portion, the edge of said diaphragm being disposed within the gap formed by said cap and said container to effect a gas tight and liquid tight seal between said cap and said container, said diaphragm spanning the opening of said container underneath the arched portion of said cap, and a spacing member integral with and surrounding the center section of said diaphragm, said spacing member projecting from said diaphragm intermediate said diaphragm and cap and being normally spaced from said cap.

5. A vent structure for an electrolytic device having a container, subject to internal excess gas pressure, said vent comprising an apertured cap secured to an opening of said container, said cap having a rim forming a narrow gap therebetween and said container, a flexible diaphragm having a rim disposed within said gap, the rims of said cap and said diaphragm being spun over with the edge of said opening to effect a liquid tight seal between said cap and said container, said diaphragm being normally spaced from said cap and having a central section of lesser thickness than its outer portion with a normally closed puncture therein, and separating means intervening between said diaphragm and said cap exterior of said center section and normally spaced from said cap.
